UNITED STATES PATENT OFFICE.

JOHN BELMOR ARMSTRONG, OF GUELPH, CANADA; ROBERT TORRANCE
ADMINISTRATOR OF SAID ARMSTRONG, DECEASED.

APPARATUS FOR SHAPING, HARDENING, AND TEMPERING STEEL PLATES, &c.

SPECIFICATION forming part of Letters Patent No. 499,368, dated June 13, 1893.

Application filed April 19, 1892. Serial No. 429,699. (No model.)

To all whom it may concern:

Be it known that I, JOHN BELMOR ARMSTRONG, a subject of the Queen of Great Britain, residing at the city of Guelph, in the 5 county of Wellington, Province of Ontario, Canada, have invented certain new and useful Improvements in Apparatus for Shaping, Hardening, and Tempering Steel Plates, &c.; and I hereby declare the following to be a full, clear, and exact description of the same, reference being had to the accompanying drawings, wherein—

Figure 1 is a plan view of the shaping apparatus embodying my invention. Fig. 2 is 15 a side elevation of the same, the hardening tank in section to show the mechanism for receiving the plate and uniformly delivering the plate to the hardening bath. Fig. 3 is an enlarged perspective view of the truck. Fig. 20 4 is a sectional view of the tank with elevation of the hoist and carrier, embracing the mechanism for conveying the plates from the hardening tank to the tempering ovens, and Fig. 5 is a view of the end of the tempering 25 oven the left hand door being removed.

Like symbols refer to like parts wherever they occur.

My invention relates to the construction and arrangement of apparatus for shaping, 30 hardening, and tempering metal plates, and though of general utility for all classes of plates, has been especially devised for the shaping, hardening and tempering of carriage springs, which require to be very uniform in character.

It is a well recognized fact that in bending and hardening metals, in order to obtain the best results, it is desirable not to heat the metal above the temperature required for 40 bending the same; and, where uniform results are desirable the several plates or pieces, should be immersed in the hardening bath in as nearly the same position or manner as possible.

45 The objects of the present invention are, therefore, to produce a machine adapted to automatically effect the steps of bending and immersing the plate or like article, so as to avoid the loss of time and heat incident to 50 the present methods and apparatus employed.

To this end, the main feature of my invention embraces the combination with bending mechanism and the hardening tank of interposed mechanism adapted to automatically transfer the article from the bender to the 55 bath.

A secondary feature embraces the combination with the bath or tank and carrier for conveying the articles to the tempering ovens 60 of an interposed hoist.

There are other features of invention relating to particular features of construction and specific combinations, all as will herein-after more fully appear.

I will now proceed to describe my invention 65 more fully, so that others skilled in the art to which it appertains may apply the same.

In the drawings, A, indicates the bed of the bending machine supported by posts a, a or otherwise arranged so that a hardening tank 70 H, may be placed below or in suitable relation to the formers thereon. Journaled in boxes on the frame or bed A, is a crank shaft B, provided with one half b of a clutch adapted to engage the other half c thereof, the said 75 half c, being attached to or formed with a band wheel C, loosely journaled on the crank shaft and by means of which the power is intermittently applied to said crank shaft. A ratchet spring b' is provided which engages 80 the clutch section b, and arrests the crank when at the extremity of its backward stroke.

B' indicates a suitable treadle for controlling the sliding clutch section b.

D, indicates a ram which moves in guides 85 D', D' on the frame or bed A, said ram being adjustably connected with the crank shaft B by right and left hand threaded sections d, d', and similarly threaded collar d'', which form a turn-buckle attachment between said 90 parts.

Secured to the ram D is one section E of the former or shaping mechanism and adjustably secured to the bed or frame A of the machine is the other section E', of said former, or shaping mechanism the bed A being slotted as at F to permit the escape of the bent plate or other article on the recession of section E. Adjustably secured to the bed A, at each end 95 of the section E of the former or shaping 100

mechanism is a support d^3 , or holder which holds conjointly receive the ends of an article and retain it in position until the advance of section E grips the article and carries it forward against the former section E'.

Below the bed A of the machine and beneath the formers E E' or shaping mechanism is arranged the hardening tank H for the reception of the oil bath or its equivalent, and interposed between the formers and said tank is the mechanism which receives the article from the formers or shaping mechanism and immerses it in the bath. Said mechanism is preferably a rock-shaft F', provided with a series of fingers f f f, and at one end with a crank arm F², at a suitable angle to said fingers and connected with a second rock-shaft F³ by a rod or link f', the rock-shaft F³ being in turn provided with a crank arm f² and connected with the ram D by a toggle f³ (shown in dotted lines Fig. 2) or in any other suitable manner, which will cause the said fingers f to rise with the advance and drop with the recession of the ram D.

The hardening tank H is provided, on that part of its bottom which is beneath the bed A of the machine, with a track h for the reception of a truck G, and also with an inclined guide h', which extends downward in a plane parallel with the plane of the fingers f f f, when the latter are in their lowest position (see Fig. 2), and the end of said tank H, which extends beyond the side of bed A, is provided with a hoist or lift I, the purpose of which will hereinafter appear.

G indicates a truck adapted to travel on the track h in the tank H. The bed or frame of said truck is composed of two parts g and g', one of which is hinged at one side so that it can be raised on an inclination in line with the fingers f f f, and parallel with the guide h' (see Fig. 2), and in order to secure it in said position, a catch g², is provided which may be located either on the under side of bed A, or on the tank H, as preferred. The part g' thus becomes a movable incline adapted to receive the article from the transfer mechanism F', f f f, and when full to be lowered into a horizontal position and transferred from beneath the guide h' to the hoist I and thence to the carrier K.

Arranged in one end of the tank H is a lift or hoist I, the lower rails of which form a continuation of track h when the lift is in its lowest position. Arranged in line with the lift is a suitable overhead track on which travel the wheels k k from which is suspended a suitable carrier K, having rails k' k², &c., at different heights corresponding to the number of trucks the height of the tempering oven will admit.

Any well known arrangement of tracks, switches and tempering ovens may be used, and therefore to avoid complicating this specification I have only shown the doors of the tempering oven O, (see Fig. 5) and the rails or ledges o' o², &c., corresponding in ar-

rangement with the rails k', k², &c., of the carrier.

In order to keep the oil or other hardening bath in tank H, cool or at an even temperature, and thus aid in producing uniform results, I cause the same to circulate through a coil L (see Fig. 4), immersed in a tank M, of running water, and if desired, the circulation may be forced by means of any of the well known forms of pump, and a low temperature maintained by equally well known refrigerants.

The apparatus, being constructed and arranged, substantially as hereinbefore set forth, will operate as follows: The plate to be shaped, hardened, and tempered (which in the present instance is shown as a spring s) is heated but little if any above the temperature required to harden it, and is then placed in the supports d³. The treadle B' is depressed by the foot of the operator which causes the clutch section b to engage clutch section c on the band wheel C and impart an advance movement to the ram D and attached former section E of the shaping mechanism. The foot is immediately withdrawn from the treadle which causes the spring dog b' to arrest the ram on its reverse movement or when it is at the extremity of its backward travel. When the ram D and its former section E, advances, as before specified, it bends and shapes the article s and in so doing pushes its ends off the supports. This advance movement of the former section E and ram D has through the toggle f³ (see dotted line Fig. 2), rock-shaft F³ and link or rod f' actuated rock-shaft F' so as to bring the fingers f f f, up into the position shown in Fig. 1, and the reverse motion of the ram D which releases the article s and permits it to fall on the fingers f f f, causes the return movement or dropping of said fingers to the position shown in Fig. 2, thus delivering the article on the inclined hinged frame g' of truck G, beneath the guide h' which causes every article thus delivered to enter the hardening bath in the same position and manner. The whole operation of bending and hardening being automatic and so rapid that there is no appreciable loss of heat by the article between the heating furnace and the bath. When the hinged frame g' of the truck has been filled, the truck is pushed to the end of the track and upon the lift I (see Fig. 4) and is then raised out of the bath and allowed to drip until the next truck is filled, after which it is run upon the upper rail of carrier k⁴. The succeeding truck having been filled is in turn allowed to drip and is then transferred to the next rail k³ of the carrier, and so on until the carrier is full, when it is run along the track to the oven O, the tracks k', k², &c., of the carrier brought in line with the ledges o', o², &c., of the oven O and the trucks pushed into the oven. When the tempering oven O is filled it is closed and the temperature of the oven is maintained at the required heat to temper the springs or other articles in the usual manner.

Having thus described my invention, what I claim, and desire to secure by Letters Patent, is—

1. In apparatus for shaping and hardening metals, the combination with shaping mechanism, and a hardening bath arranged beneath said shaping mechanism, of interposed vibratory transfer fingers, and means for actuating said fingers; substantially as and for the purposes specified.
2. In an apparatus for shaping and hardening metals, the combination with shaping mechanism having a movable section and means for actuating it, and a hardening bath, of interposed transfer mechanism, and means for actuating the transfer mechanism from the movable section of the shaping mechanism; substantially as and for the purposes specified.
3. In apparatus for hardening and tempering metal, the combination with shaping mechanism having a movable section, and means for actuating it, of an interposed adjustable connection, a hardening bath, transfer mechanism interposed between the shaping mechanism and the bath, and means for actuating the transfer mechanism from the movable section of the shaping mechanism; substantially as and for the purposes specified.
4. In apparatus for shaping and hardening metal, the combination with shaping mechanism having a fixed section E' and a movable section E, of supports for the article to be operated on, said supports arranged at the ends of the sections, and a hardening bath arranged beneath the shaping mechanism, substantially as and for the purposes specified.
5. In apparatus for shaping metals, the combination with shaping mechanism, of a rock-shaft provided with fingers which extend beneath the shaping mechanism and receive the article when released thereby; substantially as and for the purposes specified.
6. In apparatus for shaping and hardening metals, the combination with shaping mechanism and a hardening bath or tank, of a truck adapted to travel in the tank, and interposed transfer mechanism for receiving the article operated on and delivering it to the truck; substantially as and for the purposes specified.
7. In apparatus for shaping and hardening metal, the combination with shaping mechanism and a hardening bath or tank, of a movable incline arranged in the tank, and interposed transfer mechanism; substantially as and for the purposes specified.
8. In apparatus for shaping and hardening metal, the combination with shaping mechanism and a hardening bath or tank, of a receiving incline within the tank, a guide above the incline, and transfer mechanism interposed between the former and the incline; substantially as and for the purposes specified.
9. In apparatus for shaping and hardening metal, the combination with shaping mechanism and a bath or tank, of a truck adapted to travel in the tank and provided with a pivoted frame, means for holding the pivoted frame of the truck in an inclined position, and a rock-shaft arranged beneath the former and provided with transfer fingers; substantially as and for the purposes specified.
10. In apparatus for shaping and hardening metal, the combination with shaping mechanism, of a rock-shaft arranged beneath the same and provided with transfer fingers, a tank arranged beneath the transfer fingers, a truck adapted to travel in the tank and provided with a movable frame, and a guide arranged in the tank, substantially as and for the purposes specified.
11. In apparatus for shaping and hardening metal, the combination with shaping mechanism, of a hardening bath or tank, interposed transfer mechanism, a truck adapted to travel in the tank, a carrier for conveying the articles to a tempering oven, and a hoist interposed between the tank and the carrier; substantially as and for the purposes specified.
12. In apparatus for shaping and hardening metal, the combination with shaping mechanism, of a hardening tank, having a refrigerating coil connected therewith, a truck adapted to travel in the hardening tank, transfer mechanism interposed between the shaping mechanism and the tank, and a hoist arranged in or over the tank; substantially as and for the purposes specified.

In testimony whereof I affix my signature, in presence of two witnesses, this 18th day of March, 1892.

JOHN BELMOR ARMSTRONG.
